(57) **CLAIM**

The ornamental design for a container for fuel, as shown and described.

DESCRIPTION

FIG. 1 is a front elevational view of a container for fuel showing my new design;

FIG. 2 is a rear elevational view thereof;

FIG. 3 is a right side elevational view with the left side being a mirror image thereof;

FIG. 4 is a top plan view thereof; and,

FIG. 5 is a bottom plan view thereof.

The broken lines shown in the drawing disclosure are for illustrative purposes only and form no part of the claimed design.
